UNITED STATES PATENT OFFICE.

GUSTAV HÜBNER, OF PLauen, GERMANY, ASSIGNOR TO WILHELM REENTS, OF BAUEN,
GERMANY.

EMBROIDERING-MACHINE.

1,137,623.

Specification of Letters Patent. Patented Apr. 27, 1915.

Application filed October 14, 1910. Serial No. 586,995.

To all whom it may concern:

Be it known that I, GUSTAV HÜBNER, subject of the German Emperor, and residing at 2 Pfaffenfeld street, in Plauen, (Vogtland,) 5 Kingdom of Saxony, in the German Empire, have invented certain new and useful Improvements in Embroidering-Machines, of which the following is a specification, reference being had therein to the accompanying drawings.

This invention relates to embroidering frames of embroidering machines and pertains more particularly to means for adjusting such frames to insure that a definite position of the embroidering frame corresponds automatically with each hole of the pattern card.

The novelty resides in the particular construction and arrangement of parts herein- 20 after more fully described and then pointed out in the appended claims.

The invention is clearly illustrated in the accompanying drawings, which, with the characters of reference thereon, form a part 25 of this specification, and in which—

Figure 1 is a side elevation of my improved mechanism, omitting the toothed wheel segments. Fig. 1^a is a detail in top plan with portions removed. Fig. 1^b is a similar view showing some of the same parts in different position. Fig. 2 is a detail in elevation showing the lower portion of the device. Fig. 3 is a similar view with the parts in a different position. Fig. 3^a is an 30 enlarged detail, partly in elevation and partly in vertical section, showing one of the contact levers and coöperating parts. Fig. 3^b is a top plan of the parts shown in Fig. 3^a with a portion removed. Fig. 4 is an elevation of the parts shown in the upper portion of Fig. 1. Fig. 5 is a side elevation with portions in section, of a plurality of toothed segments in connection with an equal number of screw spindles. Fig. 6 is a plan 45 view of the parts seen in Fig. 5.

Like letters of reference indicate like parts throughout the several views.

Referring to the drawings, the base *b* supports the side walls *a* which serve to support the operating parts soon to be described.

c is the main drive shaft carrying a crank disk *d* shown in the form of a toothed wheel.

e is a pin secured eccentrically to said disk and surrounded by the eye *f* of the connecting rod *g*, the upper end of which con-

necting rod is pivotally connected with one arm of a lever *h* which, in turn, transmits motion to the axle *i* carrying a block *k*, said axle passing through a slot *l* in the arm *n* suitably guided in its movement so that said 60 arm *n* is given a pendulous movement which is transmitted to the frame *q* provided with rods *o* which are provided with lateral pins or the like *o*⁹ working in vertical slots *o*¹⁰ in the arms *o*¹¹ which carry the toothed segments *p* which are mounted for movement upon the shaft *p*⁹ for a purpose which will be described.

It is to be understood that the number of frames *q* corresponds to the number of holes 70 in the first row in the pattern card, and in order that these frames may be displaced each time to the right when the contact levers which engage with the pattern card enter the holes, I provide the following 75 mechanism, reference being had to Figs. 1, 2 and 3 wherein *s* is a wheel meshing with the toothed wheel *d*, the said wheel being mounted upon a shaft *t* carrying a disk *u*, said disk being provided with a partial eccentric groove *v* in which works a roller *y* carried by a slide or guide bar *w* attached to the rod *x*. This rod has pivotally connected throughout its upper end, as at *x*⁹, an arm *x*¹⁰ which is rigidly connected with a frame *a*' rotatable on a pivot *z*, and in this frame the contact levers *d*' *d* are situated, being mounted upon an axle *b*' supported in said frame and which contact levers are designed to contact with the pattern card *c*', the said contact levers normally resting loosely against the pattern card so that they may readily enter the holes thereof, and when this occurs with a portion of the contact levers, the roller *y*, which at this time still engages with the eccentric part of the groove *v*, comes into its highest position when a rod *h*' pivotally mounted at *h*² and which up to this time had supported itself 85 against the stationary nose *e*' and which rod *h*' is rotatably mounted on the plate *g*', is drawn forward in the direction of the arrow in Fig. 3, so that the pointed end of the plate *g*', see Fig. 3^a, grips between the rear 90 ends of the contact levers *d*' and presses them upward or downward as the case may be, see Fig. 1. When the roller *y* again enters the eccentric groove *v*, the frame *a*' assumes a sloping position, as indicated in Fig. 2, and all the contact levers *d*' which 95

100

105

110

have entered the holes of the pattern card lift by means of hook-shaped projections k' , similarly shaped projections l' of the levers n' rotatable about an axis m' , so that the arms 5 or levers n which engage the levers n' are also raised and the lower pins o' carried by said levers n contact with the lower projections p' of the frames q so that these frames are pressed to the right, owing to the oscillation of the levers, while those frames corresponding to the contact levers which did not enter the holes in the pattern card remain in their inoperative position to the left, because the contact levers are, before the 10 tilting of the frame a' , lifted so far by the plates g' that they can no longer influence the projections l' . Now, if by the oscillation of the toothed segments p which are connected as above described with the rods 15 o and the frames q , the displacement of the embroidery frame is effected, the roller y leaves the eccentric part of the groove b and the frame a' returns by gravity to its position of repose, as seen in Fig. 3. The rod 20 h' at the first movement of the frame a' , by reason of its movement upon the pin f' , glides downwardly under the slope of the nose e' , as shown in Fig. 1^b and by means of a spring g' is pressed back into its position of repose, sliding up on the nose e' to 25 the right, pushing the plate g' back into the position shown in Fig. 3, so that the contact levers d' are all set free and fall again against the pattern card, the forward movement of which is effected at each upward 30 movement of the left hand end of the frame a' by means of a pawl r' and a ratchet wheel s' , the latter being on the shaft s' over a roller on which the pattern card c' passes. 35 At the same time all the frames q are brought back to their left hand position by the descending arms n and the steps above described are repeated.

As seen in Figs. 1 and 4, the projections 40 l' are rigid with the levers n' so that the said parts l' and n' are practically one solid piece and move together.

As seen clearly in Figs. 1, 2 and 3, i' is a spring connected at one end to the pin f' 45 and at its other end to a similar pin f'' .

g' , see Figs. 1, 2 and 3, and Figs. 1^a, 1^b, 3^a and 3^b, is a plate spring secured at one end to the frame a' and serving to press backward to its position of repose the plate g' . 55 Spur wheels t' , see Fig. 5, are carried by the screw spindles v' and mesh with the geared segments p , as seen clearly in Figs. 4 and 5.

With the parts constructed and arranged 60 substantially as described, the operation, briefly stated, is as follows:—The parts e' , f' , g' , l' and g' are designed to prevent the projections k' of the levers d' which do not engage in a hole in the pattern card from lifting the levers n' corresponding to such levers d' . On the frame a' and extending the

full width thereof is the plate g' , hereinbefore referred to, and which is normally drawn to the left by the spring i' but cannot assume its dead center position because of the member h' fastened to the plate striking against the nose e' which is fixedly attached to the machine frame, as shown in Figs. 1^a, 1^b, 3^a and 3^b. When the roller y enters the concentric part of the groove u , the frame a' automatically assumes its horizontal position, when the rod h' will slide away from the nose e' , the spring i' pulling the plate g' to the left and the latter presses with its beveled portion against all of the levers d' that are not engaged in the holes 70 in the pattern card, as will be understood upon reference to Fig. 1, and thus lifting of the levers n' which are intended to remain at rest is prevented. In order that the levers n' may be turned upward at all, the frame a' 75 must assume its oblique position, as shown in Fig. 2, when if the rod h' were connected rigidly with the plate g' , the downward motion would cause breakage of either the rod h' or the nose e' . In order to prevent 80 this, the rod h' is mounted to turn upon a vertical pivot h^2 mounted in the vertical edge of the frame a' , as seen in Figs. 2 and 3. The rod h' on moving downward with the frame a' slides off from the bevel e^a of the 85 nose, while moving on its pivot, and when it reaches the lower edge of the nose it will be turned under the latter by the flat spring g' and thus will assume the position in 90 which it is indicated in Fig. 2. When the frame a' returns to its horizontal position, the rod h' expands the spring i' and slides up against the lower bevel of the nose e' 95 and the plate g' being connected with said rod moves therewith and the levers d' are 100 released. This operation is repeated *ad infinitum*.

After each forward motion of the pattern card by one row of holes, there occurs a shifting of the frames whose levers d' have 105 entered into such holes and there results a corresponding shifting of the embroidery frame.

What is claimed as new is:—

1. In embroidering machines, movably mounted frames, a main shaft, a driving crank connected thereto, a rod joined to said crank, a common axle, a pattern card, arms arranged on said common axle and slidable on said axle and controlled by means 115 of the pattern card, said axle forming means whereby said arms are put into uniform oscillatory motion and according to their height of position engaging and actuating said frames, and toothed wheel segments 120 connected to said frames whereby the embroidery frame is adjusted.

2. In embroidering machines, movably mounted frames, a main shaft, a driving crank connected thereto, a rod joined to said 130

- crank, a common axle, a pattern card, arms arranged on said common axle and slideable on said axis and controlled by means of the pattern card, said axle constituting means whereby said arms are put into uniform oscillatory motion and according to their height of position engaging and actuating said frames, toothed wheel segments attached to said frames whereby the embroidery frame is adjusted, spur wheels engaging said toothed wheel segments, screw spindles carrying said spur wheels and provided with right and left hand screw threads, and axially disposed nuts connecting said spindles.
5. In embroidery machines, movably mounted frames, a main shaft, a driving crank connected thereto, a rod joined to said crank, a common axle, a pattern card, arms slidably arranged on said common axle and controlled by means of the pattern card, said axle constituting means whereby said arms are put into uniform oscillatory motion and according to their height of position engaging and actuating said frames, toothed wheel segments attached to the frames whereby the embroidery frame is adjusted, spur wheels engaging said toothed wheel segments, screw spindles carrying said spur wheels and provided with right and left hand screw threads, axially disposed nuts connecting said spindles, pins on said arms arranged at a predetermined distance from each other, and projections on said frames engageable with said pins.
10. In embroidery machines, movably mounted frames, a main shaft, a driving crank connected thereto, a rod joined to said crank, a common axle, arms slidable on said axle and controlled by means of the pattern card, said axle forming means whereby said arms are put into uniform oscillatory motion and according to their height of position engaging and actuating said frames, toothed wheel segments attached to the frames, whereby the embroidery frame is adjusted, spur wheels engaging said toothed wheel segments, screw spindles carrying said spur wheels and provided with right and left hand screw threads, axially disposed nuts connecting said spindles, pins on said arms arranged at a predetermined distance from each other, and projections on said frames engageable with said pins.
15. In embroidery machines, movably mounted frames, a main shaft, a driving crank connected thereto, a rod joined to said crank, a common axle, arms slidably arranged on said common axle and controlled by means of the pattern card, said axle constituting means whereby said arms are put into uniform oscillatory motion and according to their height of position engaging and actuating said frames, toothed wheel segments attached to the frames whereby the embroidery frame is adjusted, spur wheels engaging said toothed wheel segments, screw spindles carrying said spur wheels and provided with right and left hand screw threads, axially disposed nuts connecting said spindles, pins on said arms arranged at a predetermined distance from each other, and projections on said frames engageable with said pins.
20. In embroidery machines, movably mounted frames, a main shaft, a driving crank connected thereto, a rod joined to said crank, a common axle, arms slidably arranged on said common axle and controlled by means of the pattern card, said axle forming means whereby said arms are put into uniform oscillatory motion and according to their height of position engaging and actuating said frames, toothed wheel segments attached to the frames, whereby the embroidery frame is adjusted, spur wheels engaging said toothed wheel segments, screw spindles carrying said spur wheels and provided with right and left hand screw threads, axially disposed nuts connecting said spindles, pins on said arms arranged at a predetermined distance from each other, and projections on said frames engageable with said pins.
25. In embroidery machines, movably mounted frames, a main shaft, a driving crank connected thereto, a rod joined to said crank, a common axle, arms slidably arranged on said common axle and controlled by means of the pattern card, said axle forming means whereby said arms are put into uniform oscillatory motion and according to their height of position engaging and actuating said frames, toothed wheel segments attached to the frames, whereby the embroidery frame is adjusted, spur wheels engaging said toothed wheel segments, screw spindles carrying said spur wheels and provided with right and left hand screw threads, axially disposed nuts connecting said spindles, pins on said arms arranged at a predetermined distance from each other, and projections on said frames engageable with said pins.

In testimony whereof I affix my signature.
GUSTAV HÜBNER.

In the presence of—

W. REENTS,
ROBERT HEINRICH NIER.
